SAFETY RAZOR AND BLADE

James Leslie Younghusband, Chicago, Ill.

Application January 19, 1942, Serial No. 427,213

4 Claims. (Cl. 30—351)

This invention relates to a safety razor and blade adapted to prevent blade rust.

Among the objects of my invention is to construct a razor blade of the safety type, so that when the razor is not in closed operating position, that the shaving edges of the blade will be spaced from contact with the head and guard to prevent rusting. Another object is to provide a razor blade so constructed that it will, without extraneous attachments or parts, itself operate to space its shaving edges from the head and guard in non-shaving position, said blade also adapted to be compressed without unusual pressure between the guard and head in closed position for normal shaving efficiency. My invention also contemplates such other objects, advantages and capabilities as will later more fully appear and which are inherently possessed by my invention.

While I have shown in the accompanying drawing a preferred form of my invention, yet I desire it understood that the same is susceptible of modification and change without departing from the spirit of my invention.

Referring to the drawing, Fig. 1 is a top plan view of my preferred construction; Fig. 2 is a front elevational view partly in section on line 2—2 of Fig. 1 showing the construction in open position; Fig. 3 is an end elevational view in open position; Fig. 4 is an end elevational view in closed shaving position and Figs. 5 and 6 are perspective views of different blade embodiments.

The usual safety razor has a head 10 having a depending screw threaded shank 11, a guard 12 having an opening 13 adapted to receive shank 11 when the razor is assembled, and a handle 14 having a screw threaded aperture 15 adapted to engage the screw threads of shank 11.

In combination with the foregoing parts, I provide in the embodiment shown in Figs. 2 and 5, a blade 22 which has a flat body portion 23 with spaced cuts 24 extending inwardly from the end or non-shaving edges 25 of the blade 22. Between the cuts 24 are spring portions 26 integrally connected with the body portion 23 by uncut neck portions 27.

Some of the neck portions 27 of spring portions 26 are bent upwardly to form upwardly bent spring portions 36 and other preferably adjacent spring portions 26 have their neck portions 27 bent downwardly to form downwardly bent spring portions 46.

Another embodiment of my blade 22 is shown in Fig. 6, wherein I provide fewer cuts 24 and spring portions 36 and 46.

10 In use, when a blade 22 is placed between head 10 and guard 12 and the handle 14 is turned until head 10 and guard 12 bring inward pressure against spring portions 36 and 46 so as to unbend said spring portions 36 and 46 and flatten them on substantially the same plane as body portion 23 and shaving edges 28 against and between head 10 and guard 12. The razor is then in position for shaving.

15 After the shaving operation is over the razor is, of course, wet. If the razor is left in closed position, water will be held between the blade and the head on one side and the guard on the other side. In this condition, the cutting edges of the blade will acquire rust spots, resulting in early deterioration of the blade, and creating a plurality of rough, broken, jagged edges which are likely to tear and stab the shaver in the next operation, instead of giving the smooth cut necessary for shaving.

20 When the ordinary razor is loosened, the blade moves against either the head or the guard and the rusting by wet contact continues.

25 The only way to prevent this with an ordinary razor is to disassemble the head, guard, blade and handle and dry with a cloth. This is annoying and dangerous.

30 With my blade, after shaving, disassembly and drying with a cloth are unnecessary. The handle is slightly turned so that spring portions 36 and 46 return toward their normal expanded positions. The ends of spring portion 36 bear upwardly against the head 10 and the ends of spring portion 46 bear downwardly against the guard 12 and space the shaving edges 28 away from contact with the head and guard. While the shaving edges 28 of the blade 22 are held spaced in this position away from contact with the head 10 and guard 12, the razor may be held under a hot water tap, and the stream therefrom will remove the accumulated hair and soap from the razor. Excess water may be easily removed by shaking the razor. There is nothing to hold water against the shaving edges 28. Evaporation will then promptly dry the edges before they rust. The life of blades and their maximum efficiency is increased.

35 Having thus described my invention, I claim:

40 1. A safety razor blade comprising a body portion having a plurality of positioning holes located on a substantially central axis, shaving edges and non-shaving end portions, said end portions having a plurality of spaced cuts extending inwardly from the margins of said end portions to form resilient portions between said cuts,

some of said resilient portions bent upwardly from said body portion and some of said resilient portions bent downwardly from said body portion so that said resilient portions are normally expanded with recesses below and above said upwardly and downwardly bent resilient portions respectively, said resilient portions adapted upon receipt of pressure to be compressed into said recesses in substantially the same plane as said body portion, said resilient portions adapted upon the release of pressure to expand away from the plane of said body portion, said resilient portions characterized by their inner extents being short of said positioning holes and on different axes therefrom.

2. A safety razor blade comprising a body portion having a plurality of positioning holes on a substantially central axis, opposite shaving edges and opposite non-shaving end portions, each of said end portions having at each side three spaced cuts extending inwardly from the margins of said end portions to form pairs of resilient portions among each group of three spaced cuts, one member of each of said pairs of resilient portions bent forwardly from said body portion and the adjacent member of each of said pairs of resilient portions bent downwardly from said body portion so that said resilient portions are normally expanded with recesses below and above said upwardly and downwardly bent resilient portions respectively, said resilient portions adapted upon receipt of pressure to be compressed into said recesses in substantially the same plane as said body portion, said resilient portions adapted upon the release of pressure to expand away from the plane of said body portion, said resilient portions characterized by their inner extents being short of said positioning holes and on different axes therefrom.

3. A rust preventing razor construction comprising a blade, a head positioned adjacent the upper surface of said blade, a guard positioned adjacent the lower surface of said blade, said blade having a body portion with a plurality of positioning holes on a substantially central axis, opposite shaving edges and opposite non-shaving end portions, said end portions having a plurality of spaced cuts extending inwardly from the margins of said end portions and adjacent the corners of said blade to form resilient portions between said cuts, some of said resilient portions bent upwardly from said body portion and some of said resilient portions bent downwardly from said body portion so that said resilient portions are normally expanded with recesses below and above said upwardly and downwardly bent resilient portions re-

spectively, said resilient portions characterized by their inner extents being short of said positioning holes and on different axes therefrom, a handle adapted to move said guard toward said head and compress said upwardly extending portions of said blade downwardly within said recesses therebelow and substantially flat against said head and said downwardly extending portions of said blade upwardly within said recesses thereabove and substantially flat against said guard, said handle also adapted to move said guard away from said head, said upwardly and downwardly extending portions of said blade then expanding and contacting the inner surfaces of said head and said guard respectively, and spacing said shaving edges including the corners of said blade away from contact with said head and said guard.

4. A rust preventing razor construction comprising a blade, a head positioned adjacent the upper surface of said blade, a guard positioned adjacent the lower surface of said blade, said blade having a body portion with a plurality of positioning holes on a substantially central axis, opposite shaving edges and opposite non-shaving end portions, each of said end portions having at each side three spaced cuts extending inwardly from the margins of said end portions and adjacent the corners of said blade to form pairs of resilient portions among each group of three spaced cuts, one member of each of said pairs of resilient portions bent upwardly from said body portion and the adjacent member of each of said pairs of resilient portions bent downwardly from said body portion so that said resilient portions are normally expanded with recesses below and above said upwardly and downwardly bent resilient portions, respectively, said resilient portions characterized by their inner extents being short of said positioning holes and on different axes therefrom, a handle adapted to move said guard toward said head and compress said upwardly extending portions of said blade downwardly within said recesses therebelow and substantially flat against said head and said downwardly extending portions of said blade upwardly within said recesses thereabove and substantially flat against said guard, said handle also adapted to move said guard away from said head, said upwardly and downwardly extending portions of said blade then expanding and contacting the inner surfaces of said head and said guard respectively and spacing said shaving edges including the corners of said blade away from contact with said head and said guard.
